J. H. TAILLEFER.
LOCKING DEVICE.
APPLICATION FILED JUNE 13, 1921.

1,437,923.

Patented Dec. 5, 1922.

Inventor:
Joseph Henri Taillefer
By

William Clinton
Attorney

UNITED STATES PATENT OFFICE.

JOSEPH HENRI TAILLEFER, OF RIGAUD, QUEBEC, CANADA.

LOCKING DEVICE.

Application filed June 13, 1921. Serial No. 477,198.

To all whom it may concern:

Be it known that I, JOSEPH HENRI TAILLEFER, a subject of the King of Great Britain, residing at Rigaud, Province of Quebec, Canada, have invented certain new and useful Improvements in Locking Devices; and I do hereby declare that the following is a full, clear, and exact description of the invention, such as will enable others skilled 10 in the art to which it appertains to make and use the same.

The present invention relates to new and useful improvements in locking devices.

The primary object of the invention is 15 the provision of a locking device which is a continuation of my former United States Letters Patent No. 1,358,036.

Another object of the invention is the provision of a locking device including a 20 pair of oppositely disposed pivoted latches with a key for manipulating the latter and forcing them to their releasing position and also means for preventing access to the lock by an unauthorized person.

25 A further object of the invention is the provision of a locking device including a keeper for engagement with the pivoted latch members so constructed as to always readily engage the same, thus saving time 30 in locking or unlocking the gate, door, or other closure to which the said locking device is attached.

With the above and other objects in view, the present invention resides in the novel 35 features of construction, formations, combinations and arrangements of parts to be hereinafter more fully described, claimed and illustrated in the accompanying drawing, forming a part of the present application 40 in which:—

Figure 1 is a longitudinal sectional view taken through a lock constructed in accordance with the present invention;

Figure 2 is an end view thereof;

45 Figure 3 is a horizontal sectional view; Figure 4 is a side elevation;

Figure 5 is a plan view of one of the keepers;

Figure 6 is a side view thereof; and,

50 Figure 7 is a side elevation of the key.

Referring now to the accompanying drawing by corresponding characters of reference throughout the several views, the numeral 7 designates in general a portion 55 of a closure such as a vestibule gate or the

like to which my improved locking device 8 is secured. This locking device 8 comprises a casing 9 formed at one end with a sleeve 10 through which one of the end members of the gate is inserted and retained 60 in position by fastening elements such as shown at 11.

The casing 9 is of rectangular hollow formation and is provided with a pair of pivoted latch members 12, the outer ends of 65 which are toothed and extend through an opening 13 provided in the end wall of the housing 9.

One end of the upper latch member 12 is bifurcated as at 14, while the corresponding end of the lower latch member is reduced as at 15 to operate within the bifurcated end 14 of the cooperating latch member.

A spring 16 serves to engage the adjacent 75 sides of the latch members 12, forcing them apart at their outer ends, as clearly shown in Figure 1.

A key opening is provided in one side of the casing 9, as shown at 17, while a suitable 80 guard 18 is positioned adjacent one side thereof to prevent the observation of the operating ends of the latches 12 in order to prevent unauthorized opening by means of making a key which will fit the same. 85

The key is shown at 19 and is provided with a reduced end 20 adapted to pass through the opening 17. Suitable lugs 21 and 22 are provided on one side thereof, the former of which engages the opposite sides 90 of the bifurcated end 14 of the upper latch member, forcing the latter upwardly, while the lug 22 engages the reduced end 15 of the lower latch member, forcing the inner ends of the said latch members apart and contracting the forward or outer ends thereof, thus releasing the same from the slot 23 formed in the transverse plate 24 of the keeper 25. 95

The outer end of the keeper 25 is flared 100 as at 26 to insure of the easy insertion of the latch members 12 therein.

An additional keeper for retaining the gate or closure in open position is indicated by the numeral 27, and is shown in Figures 105 5 and 6. This keeper comprises a base 28 having flanges 29 formed thereon, which support a stop plate 30 provided with horizontal and vertical side flanges 31 and 32 flared at their outer ends, as at 33, and with 110

a transverse plate 34 having a slot 35 for engaging the latches 12 and retaining the closure or gate in open position.

It will thus be seen that when the gate is 5 swung to open position, it will strike against the plate 30, thus limiting the movement, and by forcing the locking device in the direction of the plate 32, the latches will pass through the slot 35, thus causing 10 them to engage the opening and retaining the gate or closure in its open position.

From the foregoing description, taken in connection with the accompanying drawing, it will be manifest that a locking device for gates, doors and other closures is 15 provided, which will fulfil all of the necessary requirements of such a device, and it should be understood in this connection that various minor changes in the specific de- 20 tails of construction can be resorted to within the scope of the appended claims, without departing from the spirit or sacrificing any of the advantages of the invention.

Having thus fully described the invention, what I claim as new and desire to protect by Letters Patent is:—

1. The herein described locking device comprising a casing, oppositely operating latch members provided in said casing, the

inner ends of said latch members being interlocked, and adapted for engagement by a key.

2. The herein described locking device comprising a casing having an opening in the end thereof, pivoted latch members mounted within the casing and projected through said opening, a spring engaging the latch members for forcing them to locking position, the inner ends of the latch members being interlocked, and being adapted 40 for separation by a key.

3. The herein described locking device comprising a casing, said casing having an opening in one end thereof, upper and lower latch members pivoted within the casing 45 and projecting through the opening in the end thereof, one of said latch members being bifurcated and the other of the latch members being reduced and fitted therein, a key opening in said casing, and a key 50 passing through said opening and having projections thereon for engaging the interlocking ends of the latch members, substantially as and for the purposes set forth.

In witness whereof I have hereunto set 55 my hand.

JOSEPH HENRI TAILLEFER.
